UNITED STATES PATENT OFFICE.

CRAIGIE GYLE BORTHWICK, OF CORSTORPHINE, SCOTLAND.

GOLF AND LIKE BAG.

1,410,989.

Specification of Letters Patent. Patented Mar. 28, 1922.

Application filed December 15, 1920. Serial No. 430,858.

To all whom it may concern:

Be it known that I, CRAIGIE GYLE BORTHWICK, a subject of the King of Great Britain and Ireland, and a resident of Corstorphine, 5 Midlothian, Scotland, have invented new and useful Improvements in or Relating to Golf and like Bags, of which the following is a specification.

My said invention relates to self supporting golf and like bags of the tripod type in which one member of the tripod is fixed to the bag, whilst the other two members are operated transversely and laterally through springs, and held in their closed position by 15 means of a latch, and has for its object to improve and simplify the construction and action of such devices. The improved device can be readily attached to, or detached from, a bag, and is equally applicable to existing, or new, bags.

In carrying out my invention the device may be made of any suitable material, and consists of three legs forming the tripod. One of these legs has fixed to it near its 25 upper end a plate, the lower edge of which has formed on, or fixed to it, at each side a lug, and the adjacent faces of said lugs are preferably of a semi-circular form, for a purpose to be hereinafter referred to. The 30 other two legs, near their upper ends, are each pivoted to a spindle or rod passing through a casing, and the upper ends of said legs are connected by a spring. The casing is connected to the plate by a spindle or rod, 35 which passes through lugs on the latter, and this spindle is also provided with a spring.

The plate fixed to one leg, is attached near the top or mouth of the bag in any suitable manner, and the lower end of this leg is 40 connected to the lower end of the bag. It is preferred that this leg be slightly longer than the other two legs.

In order that my said invention and the manner of performing the same may be 45 properly understood I hereunto append two sheets of explanatory drawings to be hereinafter referred to in describing my invention.

Figure 1. is a back elevation of a golf bag provided with the improved supporting device. Figures 2, and 3, are respectively a side elevation, and a back elevation, showing the device in its acting position. Figure 4. is a back elevation, drawn to a larger 55 size, and showing the casing in dotted lines

so as to expose the interior, and Figure 5. is a bottom plan view. In these drawings the same reference letters are used to mark the same or like parts wherever they are repeated.

As shown in Figures 2, and 3, of the drawings, the golf bag A, is supported in an inclined position by means of three legs B. C. and D. forming a tripod. One of these legs B, which is positioned inside the bag A, 60 has fixed to it near its upper end a plate E, provided at its lower end with lugs F, F¹, one on each side, the adjacent faces of said lugs being of a semi-circular form (Figure 5) for a purpose to be hereinafter referred to. The other two legs C. and D, are each pivotally supported on pins G. and G¹, passing through a casing H, and the upper ends of said legs are, as shown in Figure 4, connected to each other by a spring J. The casing H, is connected to the plate E, by a spindle K, which passes through lugs L. M. on the latter, and this spindle is provided with a spring N.

The plate E, is attached near the top, or mouth, of the bag A, to the leg B, by means of screws P, and the lower end of this leg is attached to the bag at or near its lower end, and it is preferred that this leg B, be slightly longer than the other two legs C. and D.

If desired, and when not in use, the lower ends of the two free legs C. and D. of the tripod, may be attached to the bag A. by a strap R. (as shown in Figure 1) clip, or the like.

The device is used as follows:—It is assumed that the device has been fixed to the bag A. with the two free legs C. and D. in their closed position, as shown in Figures 1, and 5, that is to say, lying within the semi-circular lugs F, F¹, which serve as stops. In this position these legs are nearly parallel to each other, comparatively close together and lie flat against the bag A. When it is desired to use the device to support the bag A, the two legs C. and D. are drawn towards each other, thus extending the spring J, whilst at the same time clearing the lugs F, F¹, on the plate E, and as the spring N, (one part of which bears against the plate E, and the other part against the casing H) is in compression it reacts to force out the legs C. and D, whilst at the same time the spring J, extends them into their acting or supporting position, as shown in Figures 2,

and 3. To return the legs C. and D, to their closed position, it is only necessary to grasp them near the top, draw them together, and pass them inwards against the bag, in which position the spring J, will automatically force them into contact with, and retain them within, the lugs F. and F¹, as shown in Figure 4.

What I claim is:—

- 10 1. A supporting device for golf bags and the like comprising a pair of supporting members, a casing to which said members are pivotally connected adapted to be hingedly connected to a bag, said members being extensible relatively and relative to the bag, and means for retaining said members in closed position against the bag.
- 15 2. A supporting device for golf bags and the like comprising a pair of supporting members, a casing to which said members are pivotally connected, a plate hingedly connected with said casing and adapted to be secured to a bag, said members being extensible relatively and relative to the bag, and means for retaining said members in closed position against the bag.
- 20 3. A supporting device for golf bags and the like comprising a pair of supporting members, a casing to which said members are pivotally connected, a plate hingedly connected with said casing and adapted to be secured to a bag, means for extending said members relative to each other, and means for retaining said members in closed position.
- 25 4. A supporting device for golf and like bags, comprising a casing, two members adapted to form with a bag a tripod, said members being pivotally connected to said casing, a plate adapted to be fixed to the bag to which said casing is pivoted, means for automatically extending said members relative to the bag, means for extending said members relative to each other, and means for retaining said members in their closed position.
- 30 5. A supporting device for golf and like

bags, comprising a casing, three members forming a tripod, one of said members being adapted to be rigidly fixed to a bag and the other two members being movably connected to said casing, a plate adapted to be fixed to the bag, a spindle pivotally connecting said casing to said plate, a spring associated with said spindle and adapted to extend said casing and members carried thereby relatively to the bag, means for extending the free members relative to each other, and means for retaining said members in their closed position.

60 6. A supporting device for golf and like bags, comprising a casing, a bag and three members forming a tripod, one of said members being rigidly fixed to the bag and the other two members being movably connected to said casing, a plate fixed to the bag to which said casing is pivoted, means for automatically extending the free members relative to the bag, a spring for extending the free members relative to each other, and means for retaining said members in their closed position.

65 7. A supporting device for golf and like bags, comprising a casing, a bag and three members forming a tripod, one of said members being rigidly fixed to the bag and the other two members being adjustably connected to said casing, a plate fixed to the bag to which said casing is pivoted, means for automatically extending the free members relative to the bag, means for extending the free members relative to each other, lugs secured on said plate and a spring connection between the free members for retaining said members in their closed position.

70 75 In testimony whereof I have signed my name to this specification in the presence of two subscribing witnesses.

CRAIGIE GYLE BORTHWICK.
